UNITED STATES PATENT OFFICE.

WILLIAM P. THOMPSON, OF LIVERPOOL, ENGLAND.

MARINE PROPULSION.

No. 904,285.

Specification of Letters Patent.

Patented Nov. 17, 1908.

Application filed November 20, 1908. Serial No. 181,999.

To all whom it may concern:

Be it known that I, WILLIAM PHILLIPS THOMPSON, subject of the King of Great Britain, and a resident of Liverpool, in the county of Lancaster, in the Kingdom of England, civil engineer, (whose post-office address is 6 Lord street, Liverpool aforesaid,) have invented certain new and useful Improvements in Marine Propulsion.

10 This invention has for its object an arrangement of steam or other motor driven vessel, whereby it can be propelled with greater velocity and with less power than has hitherto been considered practicable, the 15 vessel being supported on fins resembling the aeroplanes of aerial navigation, and hereinafter called aquaplanes.

The invention is best described by aid of the accompanying drawings, of the well 20 known steamship *Turbinia* as it would appear fitted with my mechanism, in which

Figure 1 is a side view of the vessel when going at full speed; Fig. 2 a view from the stern of same; Fig. 3 a detail view of supporting fin; Fig. 4 an alternative view similar to Fig. 1; Fig. 5 a detail view of two supporting fins, in this instance with their levers; Fig. 6 a third variation in which the fins are fixtures but are set oblique not 30 merely longitudinally, but also transversely; and Fig. 7 a fourth modification showing supporting fins and struts projecting from the side of the hull while the vessel rides on the lowest ones which are below the ship.

35 Like letters relate to like parts in all the drawings.

Referring first to Figs. 1, 2 and 3; A is the hull of the ship, B B continuations of the keel extending to a considerable distance 40 below the hull. C C a series of supporting fins projecting from the side of the ship formed of steel, bronze, or other like hard tough metal, and having a sharp edge, front and back, and set at an angle of say four 45 degrees with the horizontal higher in front than at rear. These fins are arranged in pairs or trios at different heights. In the drawing, there are eighteen fins arranged at six different heights. D, a series of struts 50 from the hull to the fins so as to support them. For a small vessel these struts may not be required. For medium sized vessels one strut holding the end will suffice. For large vessels two or more struts on each side 55 may be requisite. These struts are made

with sharp edges fore and aft in order to lessen the friction in the water, but are otherwise tubular in large vessels for strength and rigidity. E is a beam swiveling on the driving axle F. There are one or more of these at each side of the vessel. G is a chain gear connecting the driving axle with the axle H of the paddle wheel I; there are the same number of paddle wheels as there are beams. J is a gear for raising and lowering the paddle wheel. The paddle wheel is formed as a hollow drum with a large series of radial blades K passing through slots in the same. These blades can be fixtures or have any convenient device such as a spiral cam not set forth in the drawing, for drawing them in uniformly towards the center, or projecting them through each of the slots. T T are the ordinary screw propellers of the *Turbinia*.

In Figs. 4, 5 and 6 instead of the fins being arranged at different heights, they are all in the same plane, but they are made to swivel on journals P in bearings in the keel and struts and are furnished with levers L 80 passing up through wells O O in the hull, and oscillating with the journals P as pivots. It is obvious that all of the fins or any number of them, may be connected for simultaneous movement. Fig. 6 shows a third 85 variation in which the fins are set at an angle transversely as well as at a slight obliquity longitudinally.

In Fig. 1 is shown how the paddle wheel slides in a sliding bearing in a circular slide 90 having the center of the curve in the driving axle. In this H is the axle of the paddle wheel, Q axle box, R circular guide slide.

The mode of action is as follows:—The ordinary propellers are set going till between twenty and thirty miles an hour, the vessel rises on the fins. The paddle wheel being lowered sufficiently into the water to act on the water, the engines, by friction gearing, or other mechanism, are put in gear with the paddle wheels which are thus set going, while the screws are thrown out of gear with the engine. The water coming against the fins has a tendency to raise the vessel higher out of the water, and consequently afford less resistance to the water. The power thus saved is devoted to increasing the speed of the vessel, and from time to time, or continuously, or automatically as the vessel rises, the paddle wheel is lowered 100 105 110

so as to always keep in contact with the water. This can be done automatically if the beam and the paddle are weighted sufficiently.

5 Referring now to Figs. 4 and 5 where the fins are all at the same level. This plan is only applicable for calm water such as small lakes, canals and rivers. The fins at start are at a steeper fore and aft slope with the 10 horizon and are fewer in number than in the last case, but as the ship tends to rise on them they are gradually brought to more and more nearly approach the horizontal, and thus give less resistance at increased 15 speeds instead of as before mentioned rising out of the water. In Fig. 6, the fins are placed oblique longitudinally as well as transversely, so that as the vessel rises a less area of fins is submerged.

20 In Fig. 7 some of the fins project from the side of the ship and only a few are below the hull. As the vessel rises the former are exposed; these are hinged and their struts likewise, so that they can both be folded up 25 against the hull during the voyage and while in dock.

I do not bind myself to the exact arrangement of propelling devices, as I am fully aware that my supporting fins could be used 20 with screw propulsion vanes or other propellers, alone if placed sufficiently low, or with paddle wheel alone, nor is it absolutely necessary to have side beams E, as the axle box of the paddle wheel is arranged to travel 25 in a curved guide in a circular curve having the axis of the driving axle for the center. It will be noted that the fins are all disposed above the base line of the keel and while 30 they may be connected to the keel, the false keel, or the hull, the term vessel as used in the claims, is intended to cover any arrangement where the fins are in a line above the base line of the false keel, keel or any extension thereof.

45 Having thus described my invention, what I claim as new and desire to secure by Letters Patent, is:—

1. A vessel having a plurality of long narrow supporting fins or aquaplanes under the 50 hull, projecting out beyond the gunwale and directly connected to the body of the vessel.

2. A vessel and a series of long narrow supporting fins or blades having their inner ends connected to the body of the vessel on 55 each side of the center line and extending beyond the gunwale, said fins being disposed at short intervals for nearly the entire length of the vessel, whereby every part of the vessel is supported.

60 3. In a vessel supported by fins when traveling above the surface of the water, a series of long narrow supporting fins or blades projecting from the vessel on each side of the center line and extending beyond 65 the gunwale, said fins being disposed at

short intervals for nearly the entire length of the vessel, whereby every part of the vessel is supported.

4. In a vessel supported by fins, a series of long narrow fins having their inner ends 70 connected to the body of the vessel and extending out from the center line of the vessel on both sides to points beyond the gunwale and upon which the vessel rests when going at quick speed, whereby there is a 75 large length of cutting edge compared with the vertical area or depth of fin surface, said fins being disposed at short intervals for nearly the entire length of the vessel, whereby every part of the vessel is supported. 80

5. In a vessel supported by fins, a series of long narrow fins extending out transversely from the center line of the vessel at intervals along the length of the vessel to beyond the 85 gunwale on both sides, and upon which the vessel rests when going at quick speed, whereby there is a great length of cutting edge compared with the vertical area or depth of fin surface and every part of the 90 vessel is supported.

6. In a vessel supported by fins, a series of long narrow fins or blades carried by and projecting from the vessel on each side of the center line to points beyond the gunwale, 95 and set at a given slight angle fore and aft with the horizontal, said fins being disposed at short intervals for nearly the entire length of the vessel, whereby every part of the vessel is supported. 100

7. In a vessel supported by fins, a series of long narrow fins or blades directly connected to and projecting from the vessel on each side of the center line to beyond the gunwale, and set at a given slight angle fore 105 and aft with the horizontal.

8. In a vessel supported by fins, a series of long narrow fins fixed to and projecting from both sides of the vessel to points beyond the gunwale, said fins being disposed at a slight angle to the horizontal, to present a maximum of cutting edge, and a minimum of obstruction to advancement through air and water, said fins being disposed at short intervals for nearly the entire length 115 of the vessel, whereby every part of the vessel is supported.

9. In a vessel supported by fins, a series of long narrow fins fixed to and projecting from both sides of the vessel to beyond the 120 gunwale, said fins being disposed at a slight angle to the horizontal in a direction fore and aft, so as to present a maximum of cutting edge and a minimum of obstruction to advancement through air and water, and arranged at short intervals for nearly the entire length of the vessel. 125

10. In a vessel supported by fins, a series of long narrow supporting fins or blades projecting from the vessel on each side of the 130

center line to points beyond the gunwale and capable of adjustment as regards fore and aft slope, said fins being disposed at short intervals for nearly the entire length of the vessel, whereby every part of the vessel is supported.

11. In a vessel supported by fins, a series of long narrow transverse supporting fins or blades, attached to the vessel and arranged at intervals in the length, and extending beyond the gunwale, and capable of adjustment as regards fore and aft slope.

12. The combination with a vessel having a keel piece, of a series of long narrow fins or blades connected directly to the same and extending out laterally on each side of the center line to points beyond the gunwale at short intervals for nearly the entire length of the vessel, whereby every part of the vessel is supported.

13. The combination with a vessel of a series of long narrow fins or blades connected directly to the vessel, the blade surface extending out laterally on each side of the center line beyond the gunwale, and supported at their outer ends from the side of the ship.

14. A vessel having a hull, a keel, and a series of long narrow supporting fins projecting at intervals laterally, from each side of the vessel to points beyond the gunwale, and for the most part situated below the bottom of the hull, said fins being set at a slight angle with the normal surface of the water and the united sets of fins having sufficient area at the speed used and the angle at which they are set, to support the whole hull clear of the water.

15. A vessel having a hull, a keel and a series of long narrow supporting fins projecting at intervals laterally from each side of the vessel, and for the most part situated below the bottom of the hull and extending out beyond the gunwale, said fins being set at a slight angle with the normal surface of the water fore and aft, and the united sets of fins having sufficient area at the speed used and the angle at which they are set to support the whole hull clear of the water.

16. In a vessel, the combination with a hull and keel piece, of a series of long thin sharp-edged supporting fins having their inner ends connected to the vessel and projecting out laterally therefrom to points beyond the gunwale, said fins having their forward edges slightly higher than their after edges and some parts of the series of fins being at a much higher level than other parts, whereby when the vessel is low in the water practically the entire fin surface is submerged, but as it rises less and less of the aquaplane surface is submerged.

17. In a vessel, the combination of an ordinary hull, a keel piece, and a series of long thin sharp-edged supporting fins projecting out laterally to beyond the gunwale from

each side of the vessel, the fin surface being at varying heights whereby when the vessel is low in the water all the fin surface is submerged, but as the vessel rises, the fin surface submerged continually lessens, while at the same time the extended base remains the same, and thus great stability is insured.

18. In a vessel supported by fins, a series of long narrow supporting fins, each having its inner end connected to the vessel, said fins projecting at intervals laterally from each side of the vessel, and for the most part situated below the bottom of the hull and extending from side to side to a greater distance than the beam of the vessel, said fins being set at a very slight angle with the normal surface of the water and the united sets of fins having sufficient area at the speed used, and the angle at which they are set to support the whole hull clear of the water, whereby while there is an immense length of cutting edge and narrow surface afterwards, there is very little breadth and impediment in the water to the forward movement of the vessel.

19. In a vessel supported by fins, a series of long narrow supporting fins projecting at intervals laterally from each side of the vessel, and for the most part situated below the bottom of the hull and extending from side to side to a greater distance than the beam of the vessel, said fins being set at a slight angle with the normal surface of the water and the united sets of fins having sufficient area at the speed used, and the angle at which they are set to support the whole hull clear of the water, whereby while there is an immense length of cutting edge and narrow surface afterwards, there is very little breadth and impediment in the water to the forward movement of the vessel.

20. In a vessel wholly or largely supported by fins, the combination of a hull, a series of narrow blade fins projecting out below the hull from the center line to beyond the gunwale of the vessel, on each side the outer ends being supported by stays from the hull.

21. In a vessel supported above the surface of the water by fins, the combination with the keel, of a series of long narrow fins projecting from each side of said keel, journals having bearings in the keel and connected to said fins, and adjusting mechanism connected to said journals, whereby the angle with the horizontal at which said blades are set may be altered while the vessel is moving.

22. In a vessel supported by fins, a series of fins projecting from the side of the vessel hinged and supported at their outer ends by removable struts from the side of the vessel, whereby the fins can be folded up as they enter into dock.

23. In a vessel supported by fins, a series of hinged supporting fins extending out

laterally from the hull or keel piece to beyond the beam, and means for permitting the folding of the fins when they are not required.

5 24. The combination with a hull, of a series of supporting fins projecting from the vessel laterally, hinges on these fins, hinged struts from the vessel projecting outwards and downwards and rigidly holding the 10 ends of the fins whereby by disconnecting them, the struts can hang down and the ends of the fins be drawn up against the sides of the vessel when entering dock.

25. In a vessel, the combination of a hull, 15 a keel piece, a series of supporting fins on each side thereof, said fins supported by spindles passing through the keel piece, and having also journals at their outer ends, struts carrying these journals, and means 20 for turning the fins on their axes.

26. The combination of a series of hinged supporting fins, hinged struts holding the ends of the fins, so that when coupled they are incapable of being displaced but capable 25 of being uncoupled at will, whereby both the strut and the hinged end of the fin can be drawn out of the way when entering a dock.

27. In a vessel supported by fins, a plurality of long narrow fins projecting on each 30 side from the center line below the vessel at intervals along the entire length of the vessel to beyond the beam of the vessel, means for supporting said fins including struts secured to the sides of the vessel and connected 35 to said fins, whereby a very great width of long narrow cutting edge and blade surface is obtained and the stability of the vessel is secured.

28. In a vessel supported by fins for reducing the draft of the vessel in proportion 40 as its speed increases, successively oper-

able propelling devices each arranged to work effectively when the vessel is immersed at a different level from the other, and wholly independent of each other.

45 29. In a vessel, supporting fins for reducing the draft of the vessel in proportion to its increase in speed, and successively operable propellers arranged respectively at different levels, and wholly independent of 50 each other.

30. In a vessel, supporting fins for reducing the draft of the vessel in proportion to its increase in speed, successively and independently operable low and high speed propellers, the lower speed propeller being in a 55 plane above the plane of the high speed propeller.

31. In a vessel, supporting fins for reducing the draft of the vessel in proportion to 60 its increase in speed, and a series of propelling devices successively and independently operable as the speed of the vessel increases.

32. The combination of a vessel capable of being supported on lateral fins when in 65 rapid motion, with a propelling device for driving the vessel at slow speed when the hull is immersed in the ordinary manner, and a quick speed propelling device capable of being put into operation as the hull rises 70 and rides on the fins, and lifts the slow speed-propelling device partially or wholly out of the water.

In witness whereof, I have hereunto signed my name this 11th day of November 75 1903, in the presence of two subscribing witnesses.

WM. P. THOMPSON.
